TOY JOCKEY

John C. Rumsey, Lawrence, Kans.

Application April 27, 1938, Serial No. 204,568

2 Claims. (Cl. 46—108)

The present invention relates to amusement devices or toys, and more particularly to toy vehicles designed for the amusement of juveniles.

Accordingly, the invention aims to provide a novel type of toy vehicle or cart which will include an animal figure and representation of a jockey, together with means actuated by movement of the toy for imparting animated motion to both the jockey and animal figure.

In its preferred form as carried out in the illustrated embodiment herein, the invention comprises a cart form of vehicle designed to be trailed by a juvenile and carrying both animal and jockey figures having appropriate joint connections for both permitting and transmitting movement between the parts, which movement is effected by operating means actuated from the axle of the vehicle.

With the foregoing general object in view, the invention will now be described by reference to the accompanying drawing illustrating one form of construction for embodying the proposed improvements, after which those features and combinations thereof deemed to be novel and patentable will be particularly set forth and claimed.

In the drawing—

Figure 1 is a central sectional elevation showing a jockey vehicle constructed in accordance with the present invention; and

Figure 2 is a plan view of the same.

Referring now to the drawing in detail, this shows a vehicle construction comprising a suitable U-shaped frame 5 of appropriate miniature form, to the front end of which is attached, by means of screws 6, any desired form of handle member 7 for trailing the vehicle. The rear ends of the frame 5 are constructed as bearings 8 for journaling the ends of an axle 9, to the opposite ends of which axle are secured, as by means of pins 10, the supporting wheels 12 which also constitute driving means, through the medium of the crank portion 14 of the axle and a pivotal link member 15, for transmitting movement to the movable parts of the construction, as hereinafter described.

A clip element 16 is fastened by screws 17 or the like to the inside of the forward end portion of the frame 5 for carrying a horizontal pivot pin 18 on which is fulcrumed the forward end of a curved supporting arm 20, the rear end of which is pivotally connected at 21 to the upper end of the operating link 15.

On the upper face of this supporting arm 20 are mounted the head and neck portions of an animal figure 22 as well as the body portion 24

of a rider representing a jockey, these parts being fastened to the arm 20 by screws 25 or the like.

The lower part of the body portion 27 of the jockey figure is provided with a pivot pin 26 for pivotally mounting the upper ends of the jockey's legs 27 at opposite sides of the supporting arm 20, the opposite ends of which legs are each provided with a pivot pin 28 representing the knee joint connection with the lower leg members 30; and the feet 32 at the lower ends of said leg members 30 are shown as rockingly supported on a cross-rod 34 mounted across the open portion of the frame 5 and supported by the opposite sides thereof (see Figure 2). Arm members 35 are also illustrated as secured by a pin 36 to the opposite sides of the upper portion of the body 21, as well as by a pin 37 to the opposite sides of the neck portion of the animal figure 22 in alignment with the representation of the check rein 38 as shown in Figure 1.

With the foregoing construction it will be apparent that as the vehicle or cart is trailed along by the juvenile, the rotation of the wheels and crank 14 will actuate the link 15, and through it, the supporting arm 20 and parts carried thereby, the movements of the figures mounted on the arm 20 being of such a nature as to simulate the running movements of the animal and carrying the jockey, and the pivoted relation of the legs 30 of the jockey also being such as to cause the same to have corresponding movements in simulation of the leg movements of a jockey riding the animal.

In order to increase the realistic effect of the operation, a spring leaf assembly is carried by one side of the frame 5, said assembly comprising a middle spring leaf 40 embraced between two relatively shorter spring leaves 41, and one end of the assembly being secured by fastenings 42 to a bracket element 43 attached to the side of the frame in such a manner as to present the free end of the middle leaf 40 in the path of a pin 44 projecting from the inner side of the wheel 12 on that side of the frame. With this arrangement, each turn of said wheel will engage and release said spring leaf 40 with a snap action, with the result that the springing and snapping engagement of the spring leaves will produce rapid sounds in imitation of those of the feet of a running animal as represented by the moving animal figure 22.

It will thus be apparent that the lifelike movements executed by the operation of the improved toy vehicle construction as well as the sounds

produced in connection with said operation are such as to be calculated to make the device have a very strong appeal to the class of persons for which it is designed; and also that the described construction constitutes a very simple and strong as well as inexpensive type of construction adapted to be economically manufactured. Moreover, while I have illustrated and described what I have found to represent a very efficient and satisfactory form of embodiment of the proposed features of improvement, I desire to be understood as reserving the right to make all changes or minor modifications which may fairly be deemed to fall within the spirit and scope of the appended claims.

What I claim and desire to secure by Letters Patent is:

1. A toy jockey vehicle comprising a frame provided with supporting wheels, a movable arm carrying an animal figure and a jockey figure, said jockey figure including legs composed of

pivoted sections forming hip and knee joints and rockably connected with the vehicle frame, and means actuated by the travel of said wheels for transmitting movement to said arm for correspondingly moving said figures to simulate the movements of a jockey riding the animal.

2. A toy jockey vehicle comprising a frame provided with supporting wheels, a movable arm carrying an animal figure and a jockey figure, said jockey figure comprising a body portion mounted on said arm and leg members formed in sections pivotally connected to form knee joints and also pivotally connected with said body portion at points representing hip joints, the feet portions of said leg members being rockably connected with the vehicle frame, and means actuated by the rolling movement of the wheels for transmitting movement to said arm for correspondingly moving said figures to simulate the movements of a jockey riding the animal.

JOHN C. RUMSEY.
